Max Steinbook, New York, N. Y., assignor to
Broil-Quik, Inc., New York, N. Y., a corpora-
tion of New York

Application November 23, 1951, Serial No. 17,495

Term of patent 14 years

(Cl. D81—10)

To all whom it may concern:

Be it known that Max Steinbook, a citizen of the United States, residing at New York, in the county of New York and State of New York, has invented a new, original, and ornamental Design for an Electric Broiler, of which the following is a specification, reference being had to the accompanying drawing, forming part thereof.

In the drawing:

Fig. 1 is a perspective view of an electric broiler illustrating my new design; and

Fig. 2 is a rear elevational view thereof.

The end of the broiler, not shown, is like the end illustrated.

I claim:

The ornamental design for an electric broiler, as shown and described.

MAX STEINBOOK.
